UNITED STATES PATENT OFFICE

JAMES W. INGLETON, OF ASTORIA, OREGON

VAPORIZER FOR HYDROCARBON ENGINES

Application filed August 18, 1925. Serial No. 50,961.

The invention relates to new and useful improvements in devices whereby oil heavier than gasoline may be used for operating a hydrocarbon engine.

An object of the invention is to provide a special vaporizing device wherein hydrocarbon oils may be vaporized by the heat of the exhaust gases of the engine and subsequently mixed with air and delivered to the main-
10 fold of the engine.

A further object of the invention is to pro-
vide a device of the above type with means
for superheating the vaporized oil after it
leaves the vaporizer and subsequent to the
15 mixing of air therewith.

A still further object of the invention is to
provide a device of the above type wherein
the vaporized oil is superheated by the heat
generated by the explosion of the gases dur-
20 ing the running of the engine.

A still further object of the invention is to
provide a vaporizing device of the above type
wherein the vaporizer is provided with a re-
movable chamber in which the vaporizing of
25 the oil takes place.

A still further object of the invention is to
provide a vaporizer of the above type
wherein the air mixing device is provided
with means for collecting the heavy oil va-
30 pors condensing therein, and for returning
said condensate to the supply tank.

These and other objects will in part be
obvious and will in part be hereinafter more
fully disclosed.

35 In the drawings which show by way of
illustration one embodiment of the invention—

Figure 1 is a side view of an engine cyl-
inder with my improved vaporizing device
40 applied thereto;

Fig. 2 is a top plan view of the same, with
a portion of the cylinder broken away to
show the superheater in the head of the en-
45 gine cylinder;

Fig. 3 is a sectional view on the line 3—3
of Fig. 2;

Fig. 4 is a vertical sectional view on the
line 4—4 of Fig. 2; and

Fig. 5 is a sectional view on the line 5—5
of Fig. 4.

In carrying out the invention, I have pro-
vided a vaporizer for vaporizing hydrocar-
bon oils, which vaporizer is provided with
an inner chamber, which chamber is in turn
surrounded by an outer chamber, through
55 which the exhaust gases from the engine may
pass for heating said inner chamber. To as-
sist in the heating of this inner chamber, I
have provided a compartment for said inner
chamber which is provided with integral 60
radiating vanes. This vaporizing chamber is
detachably connected to the compartment so
that it may be readily removed and any sedi-
ment or carbon deposits formed therein 65
cleaned from said chamber. The oil to be
vaporized is passed into this vaporizing
chamber and after said oil is vaporized, it
passes out through an opening in the wall
70 of the chamber into a pipe leading through
the wall of the compartment across the outer
chamber and through the outer wall thereof.
This pipe then leads to a superheater which
is located in the upper end of the head of the
75 cylinder. Said superheater consists of a cup-
shaped member projecting into the cylinder
and removably secured to the outer side wall
of the cylinder. This cup-shaped member is
provided with a partition which directs the
80 vaporized oil well in toward the inner end
of said member where it is subjected to the
heat of the exploding gases in the engine
cylinder. The superheated vaporized oil is
then passed into an air mixing chamber into
85 which air is drawn by the suction of the en-
gine through a suitable yielding control
valve. The mixed air and vaporized oil is
then led into a manifold leading to the en-
gine cylinder. In this air chamber there is
90 a plate on to which heavy condensing par-

ticles of oil vapor collect, and this collected condensate is led back to the supply tank so that it may be again caused to cycle through the vaporizer and superheater.

Referring more in detail to the drawings, my improved vaporizer consists of a vaporizing device 1, a superheater 2, and an air mixing chamber 3. The vaporizer is shown in detail in Figures 4 and 5, and consists of an outer chamber 4 to which is connected a pipe 5 at the upper end thereof, and also a pipe 6 at the lower end thereof. The exhaust gases pass into this pipe 5 and are utilized in heating the vaporizer. Located centrally of this outer chamber 4 is a compartment 7 having integral radiating vanes 8. This compartment 7 is rigidly secured to the upper and lower walls of the outer chamber 4 and may be formed integral therewith. Extending between the side wall 9 of the outer chamber and the side wall 10 of the compartment 7 is a baffle plate 11. There is a similar baffle plate 12 on the other side of the outer chamber. These baffle plates are so located that the exhaust gases passing in through the pipe 5 will be led in and about the radiating vanes on to the opposite side of the compartment 7, then back on to the near side thereof, and finally across and out through the pipe 6.

Located in this inner compartment 7 is an inner chamber 13 which is the vaporizing chamber for the oil. This chamber 13 is provided with a supporting flange 14 which rests on the upper end of the compartment 7. The chamber 13 and flange 14 are secured to the members forming the compartment 7 by a cap plate 15 through which suitable bolts 16, 16 pass, which bolts are threaded into the members of the compartment 7. The oil to be vaporized is led through a pipe 17, which extends through the cap plate 15, and is thus delivered to the inner chamber 13. The inner chamber is slightly spaced from the inner wall of the compartment 7 so as to insure its easy removal from the compartment 7. The oil passing into this inner chamber 13 will come in contact with the hot walls thereof, and will be thoroughly vaporized. The vaporized oil will pass out through the opening 15 in the wall of the inner chamber 13, thence into a pipe 19 which extends from the wall of the compartment 7, and also through the outer wall of the outer chamber 4. It is noted that this inner compartment 7 which is provided with radiating vanes, extends entirely across the outer chamber 4 so that the exhaust gases are compelled to cross from one side of said outer chamber to the other as above mentioned. This vaporizer as clearly shown in Fig. 1 is attached to the head of the engine cylinder which is indicated at 20. Also attached to the cylinder head 20 is a superheater 2, which superheater consists of an

inner cup-shaped member 21 having a flange 22. The side of the cylinder head is formed with an opening as clearly shown in Fig. 2, through which this cup-shaped member is inserted, and said member is secured to the cylinder by a cap plate 23 and suitable bolts 24, 24. Located in this cup-shaped member 21 is a partition 25 which extends the full height of the cup-shaped member but terminates short of the inner end thereof. The pipe 19 is attached to this cap plate 23 so that the vaporized oil passes through the cap plate and along one side of the partition 25, and then across to the other side thereof and out through a pipe 26. This pipe 26 is connected by suitable devices to an air mixing chamber 3. The air mixing chamber is provided with an air inlet port 28 which is controlled by an air valve 29. This air valve 29 is mounted in a supporting bracket 30 which is threaded into the outer end of the intake port 28. The bracket 30 is provided with the usual air intake openings or ports. The valve is mounted on a stem 31 which extends out through the bracket. The valve is held seated by means of a spring 32 which bears at one end against the bracket and at the other end against a cap 33 attached to the valve stem. The suction of the engine will open the valve 29 and draw air into the air mixing chamber. The bracket 30, of course, is provided with suitable ports to allow the air to enter and pass through the valve. The lower wall 34 of the air mixing chamber is inclined and extends substantially across the lower portion of the air mixing chamber, leaving only a comparatively small air intake passage 35. This inclined plate or wall 34 collects the heavy oil vapor condensing in the air chamber, and causes the same to accumulate at the lower end thereof and to pass through an opening 36 into a collecting chamber 37. This condensate collecting in the chamber 37 is led through a pipe 38 to the supply tank with which the pipe 17 is connected. A check valve 39 is preferably provided in the pipe 38 so as to prevent the oil from being drawn from the supply chamber directly into the mixing chamber. This air mixing chamber 27 is connected to a cylindrical valve casing 40, which valve casing is in turn connected to the head of the cylinder at 41. This valve casing is, in a sense, the intake manifold for the cylinder of the engine. There is also a pipe 42 connected to this valve casing 40. Located in the valve casing is a rotatable valve 43 which can be turned by means of a suitable handle 44. The pipe 42 leads to a gasoline or light hydrocarbon oil carburetor diagrammatically indicated at 45. When the valve is set as shown in Fig. 3, then the engine can be run on gasoline. This is for the purpose of the easy starting of the engine. As soon, however, as

the engine is well under way, then the valve can be turned so that the suction of the engine will draw from the air mixing chamber. This will cause the superheated vaporized oil to be thoroughly mixed with the air taken in through the air valve, and the mixed gas thus formed led to the engine cylinder.

While I have shown the superheater as located in the head of the engine cylinder, it will be understood, of course, that it may be otherwise located and heated. The essential feature, however, is the locating of the superheater between the vaporizer and the air mixing chamber. While I have shown the vaporizer as heated by the exhaust gases passing from the engine, it will be understood also that this vaporizer for the heavy oil may be otherwise heated.

It is to be understood that the term "vaporizer" as used throughout the description and claims, is used in its broadest sense to cover an explosive fuel generator, whether the fuel be in the form of vapor or gas. The same is true of the expression "vaporized oil". The invention is directed broadly to the changing of the hydrocarbon oils into a vapor or gas by the aid of heat. While I prefer to use my improved fuel generating device in connection with hydrocarbon oils heavier than gasoline, it will be understood that it may also be used with gasoline or other lighter hydrocarbon oils, and will be very effective, for the reason that the use of the heat will more efficiently vaporize or gasify the oil passing therethrough.

It is obvious that minor changes in the details of construction and the arrangement of the parts may be made without departing from the spirit of the invention as set forth in the appended claims.

Having thus described the invention, what I claim as new and desire to secure by Letters Patent, is—

1. A charge forming device for hydrocarbon engines including in combination, a vaporizing chamber, means for supplying hydrocarbon oil to said chamber, means for utilizing the exhaust gases from said engine for vaporizing the oil in said chamber, a superheater closed to the atmosphere projecting into the combustion chamber, means for passing the vaporized oil from the vaporizing chamber through said superheater whereby said vaporized oil is superheated and further vaporized in the absence of air, and means for mixing air with the superheated vaporized oil and directing the same to the engine cylinder.

2. A charge forming device for hydrocarbon engines comprising a vaporizing chamber, means for conducting the exhaust gases from the engine about said vaporizing chamber whereby the walls thereof are heated, means for directing a jet of hydrocarbon oil into and against the walls of said vaporizing

chamber, a superheater closed to the atmosphere projecting into the combustion chamber of the engine, means for directing the vaporized oil from the vaporizing chamber through said superheater whereby said vaporized oil is superheated and further vaporized in the absence of air, and means for mixing air with the superheated vaporized oil and directing the same to the engine cylinder.

In testimony whereof, I affix my signature.

JAMES WM. INGLETON.
